TRIMMER FOR CONTINUOUS FORM PAPER

Dana W. Mox, Glenview, Ill., assignor to Uarco Incorporated, Barrington, Ill., a corporation of Illinois

Filed Mar. 8, 1962, Ser. No. 69,154

Term of patent 14 years

(Cl. D55—1)

FIG.3

FIG.4

FIGURE 1 is an isometric view of the front end and one side of a trimmer for continuous form paper embodying my new design;

FIGURE 2 is an isometric view of the rear and opposite side thereof;

FIGURE 3 is a side elevational view of the right side thereof with the doors in open position; and

FIGURE 4 is an isometric view thereof.

I claim:

The ornamental design for a trimmer for continuous form paper, as shown and described:
